US0D1013580S

(12) **United States Design Patent** (10) **Patent No.:** **US D1,013,580 S**
Chen (45) **Date of Patent:** **** Feb. 6, 2024**

(54) **ALL TERRAIN VEHICLE FOR KIDS**

(71) Applicant: **DONGGUAN ASIWO TECHNOLOGY CO., LTD.**,
 Dongguan (CN)

(72) Inventor: **Yufeng Chen**, Dongguan (CN)

(73) Assignee: **DONGGUAN ASIWO TECHNOLOGY CO., LTD.**,
 Dongguan (CN)

(**) Term: **15 Years**

(21) Appl. No.: **29/840,970**

(22) Filed: **Jun. 2, 2022**

(30) **Foreign Application Priority Data**

May 31, 2022 (CN) 202230329884.0

(51) **LOC (14) Cl.** **12-11**

Primary Examiner — Darlington Ly

(57) **CLAIM**

The ornamental design for an all terrain vehicle for kids, as shown and described.

DESCRIPTION

FIG. 1 is a perspective view of an all terrain vehicle for kids showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the all terrain vehicle for kids that form no part of the claimed design.

1 Claim, 8 Drawing Sheets
